DESCRIPTION

FIG. 1 is a top perspective view of a toilet bowl cleaner with rotatable scrubber showing our new design;

FIG. 2 is a bottom perspective view thereof;

FIG. 3 is a left side elevational view thereof;

FIG. 4 is a top plan view thereof;

FIG. 5 is a right side elevational view thereof;

FIG. 6 is a bottom plan view thereof;

FIG. 7 is a rear elevational view thereof, taken along line 7—7 on FIG. 3, shown enlarged for ease of illustration; and,

FIG. 8 is a front elevational view thereof, taken along line 8—8 on FIG. 3, shown enlarged for ease of illustration.

The broken lines in the drawings illustrate unclaimed portions of the toilet bowl cleaner with rotatable scrubber and form no part of the claimed design.
